GAME APPARATUS

Myron C. Morrill, South Plainfield, N. J.

Application January 11, 1940, Serial No. 313,330

9 Claims. (Cl. 273—41)

The invention relates to game apparatus, more especially to a form of bowling apparatus wherein balls are rolled or played along an alley or platform to strike pins swingably suspended above the same.

It has for an object to provide in a compact and more or less portable unit swingably mounted pins and novel means for retaining a struck pin in elevated position, the particular position depending upon the degree of impact of a played ball thereon.

The invention has for another object the provision of novel means whereby all elevated pins may simultaneously be released as by electrical means operated from a remote point and restored to the normal vertical position.

A further object of the invention is to provide clutching mechanism between certain of the pins whereby these pins will be elevated not only when struck directly, but when an associated pin is struck rather than said pin.

Still another object of the invention is to so arrange the free and "clutched" pins that it becomes possible to throw a "strike" with a single ball or a "spare" with two balls, notwithstanding that all of the pins are suspended and therefore constrained to a definite plane of movement.

In carrying out the invention, provision is made for a box-like structure having parallel sides and open at the front, with a bottom preferably inclined slightly upwardly and from the front to the rear of the structure. There is provided at the rear thereof an opening from the top of the floor into a compartment or pit into which pit is received a spent ball after delivery over the floor in the playing of the game. Between the sides of the structure are located transverse rows of pins which are swingably suspended upon transverse shafts supported in the said sides.

These shafts are designed to be rotated all in one direction, and preferably simultaneously, to cause a pin or pins mounted thereon to partake of the rotation of the shaft for restoring a pin to its normal vertical position after having been struck by a ball and elevated. When such pin is struck by a ball, it will be elevated to a degree depending upon the impact and will be held in the elevated position through engagement of pawl and ratchet means, for example, as a pawl carried by and rotatable with its supporting shaft engaging an internal ratchet element through which the shaft passes and carried by a corresponding pin.

Provision is made, furthermore, through suit-

able clutch means on certain of the shafts whereby when predetermined pins are struck by a played ball an associated pin will also be elevated even though when not directly struck by the ball, such associated pin, however, when struck directly by a ball not carrying with it the first-named pin.

The nature of the invention, however, will best be understood when described in connection with the accompanying drawings, in which:

Fig. 1 is a fragmentary plan view of the pin end of the game apparatus and illustrates the novel mounting and arrangement of the pins, several of which are indicated in the upset or elevated position.

Fig. 2 is a longitudinal section thereof taken on the line 2—2, Fig. 1 of the drawings, and looking in the direction of the arrows; and Fig. 3 is a similar view taken on the line 3—3, Fig. 1 of the drawings.

Fig. 4 is a detail, fragmentary view, partly in longitudinal section, of one of the rows of pins, and viewed from the side of a pin opposite that of an on coming ball.

Fig. 5 is an enlarged fragmentary transverse section taken on the line 5—5, Fig. 4 of the drawings, and looking in the direction of the arrows.

Figs. 6, 7, and 8 are fragmentary elevations and part vertical sections of a pin and its supporting and stop means, Fig. 6 showing the pin in its normal upright position; Fig. 7, in the prone position after having been struck by a ball, and Fig. 8, in its restored vertical position.

Referring to the drawings, 10 designates a box-like structure which is open at the top and comprises the sides 11 and 12 and the bottom 13 with back or apron 14, from which depends a swingable back-stop 15. The bottom 13 is, as shown, preferably inclined upwardly toward the back wall 14 and terminates thereat in a transverse opening 16 through which a played ball passes to be returned through a trough 17 in well-known manner to the front of the game apparatus.

Between the sides 11 and 12 four parallel and horizontally disposed shafts 20, 21, 22, and 23 are rotatably mounted at successively higher locations to follow the inclination of the bottom 13. Suitable bearings for the respective shafts are provided in the opposite sides, as shown; and at one side the shafts project through to receive worm wheels 24, 25, 26, and 27, respectively, engaging corresponding worm gears 28, 29, 30, and 31, respectively, of a worm shaft driven from an electric motor 32 mounted at the side 33.

of the structure. Operation of the motor is preferably controlled from the play end of the apparatus (not shown) through a suitable control circuit indicated at 33.

On the respective shafts are arranged to swing the pins to be played; and, as shown, shaft 20 is designed to carry but a single pin 35; shaft 21, two pins 36 and 37; shaft 22, three pins 38, 39, and 40; while shaft 23 carries four pins 41, 42, 43, and 44. The arrangement of the pins is that generally adopted in standard ten pin bowling games where the pins are not suspended. The pins are designed to be elevated when their lower end is struck by a ball rolled over the floor 13, which may be extended the desired length in a direction opposite the box-like structure end.

To permit a pin to swing freely on its shaft, and at the same time to remain in elevated position after being struck and until released, a pin is mounted, for example, upon a sleeve 45, the pin being transversely bored through as at 46 to accommodate the sleeve in a more or less forced fit, and at a position such that the axis of rotation or swing of the pin may be at or, preferably, somewhat above its center of gravity. A sleeve, furthermore, is provided with an end flange or with a ring element 47 having nail or screw openings 48 through which fastening means may be driven into the pin so that the latter and the sleeve with ring become one member. The position of the sleeve with respect to the pin may be further assured by means of a screw 49 passing through the side of a pin and threaded into its sleeve.

Ring 47, moreover, is provided with an internal ratchet element 49 whose teeth are engaged by a pawl 50 mounted in the shaft upon which the pins are carried and projecting radially therefrom, being spring-urged outwardly by a coil spring 51 to engage the teeth of the ratchet in such a manner that the said teeth may ride freely thereover in the direction indicated by the arrow *a*, Fig. 5 of the drawings, when a pin is struck by a ball and swung upwardly. Of course, the pawl and ratchet means shown may be reversed, if desired.

By this expedient, no appreciable return movement of the pin is had as such return movement will be checked by the pawl engaging a tooth of the ratchet—see Fig. 7 of the drawings—and from which it will be noted that the pawl has not changed from its vertical position indicated in Fig. 6, although the pin has swung approximately through an angle of 90°. Of course, a pin may assume various intermediate positions depending upon the degree of impact.

To restore elevated pins to the normal upright position indicated in Fig. 8 of the drawings, it is necessary merely to operate motor 32 by closing the electric circuit 33 thereto. This will cause the various shafts to rotate simultaneously in the direction indicated by the arrow *b*, Fig. 5, and any pins in the prone or an intermediate position will be carried along until the lower portion of the pin engages one of the stop rods 20', 21', 22', 23' disposed immediately in front of and somewhat below the corresponding shafts 20, 21, 22, and 23. Continued rotation of the shafts will not objectionably affect the apparatus as the pawl will merely slip over the ratchet teeth, although rotation of the motor should be stopped before further balls are played.

It will be apparent that with the suspended pin type of bowling game as ordinarily arranged,

it is not possible to make a "strike" with a single ball, since each of the freely swinging pins is constrained to movement in a definite plane and is not free to be thrown about as in the case of standard bowling practice utilizing unattached pins. However, this result may be secured by the novel association herein set forth between certain pins whereby, notwithstanding that all the pins are freely swingable, certain of the pins when struck by a ball will also carry with them a further pin.

Thus, reference being had more especially to Figs. 1, 2, and 4, the first row of pins, namely that of the shaft 20, is constituted of but a single pin 35 and the next row of two pins 36, 37, each 15 freely and independently swingable. In the case of the pins mounted on the third shaft 22, however, the intermediate pin 39 is arranged to be coupled to its adjacent end pins 38 and 40, though in a manner such that if either of these end pins 20 be struck by a ball, the pin will swing freely and be elevated similarly to the pins 35, 36, and 37.

The coupling arrangement may conveniently be embodied in the sleeves for the different pins as in providing at the inner end of sleeve 45 of 25 the pin 40 a tooth 55 juxtaposed to a similar tooth 56 at the cooperating end of a divided sleeve 45' of the pin 39. The other half of this sleeve carries also a tooth 57 cooperating with a tooth 58 of the sleeve 45' of pin 38. Thus, if 30 the pin 39 be struck by a ball, the two sets of engaging teeth will cause the sleeves 45 and 45' to be carried along with sleeve 45' of the said pin 39; but if either of the pins 38 or 40 be struck, the juxtaposed teeth will separate and only the 35 particular pin struck will be elevated.

Similarly, in the case of the rearmost shaft 23, the end pins 41 and 44 may be coupled to their respective intermediate pins 42 and 43 through the clutch elements 60 and 61, respectively. The end pins may, therefore, be swung without actuation of an intermediate associated pin, for example, as indicated in Fig. 1 of the drawings, but if either of the intermediate pins 42 or 43 be struck, the corresponding associated 45 end pin will also be elevated.

The general arrangement of the pins on the shaft is such that a ball hitting the first pin 35 and passing straight through the set of pins will 50 also strike the two pins 36 and 37, the pin 39—which causes pin 38 and pin 40 also to be swung upwardly—and the two pins 42 and 43, which in turn will cause the end pins 41 and 44 to be 55 swung upwardly, thus making a "strike." The position of the pins on the shafts is fixed by suitable collars 65 and the lengths of the different sleeves.

I claim:

1. In game apparatus of the nature set forth: 60 a plurality of parallel, horizontally disposed shafts rotatably supported between the sides of a box-like structure, pins swingably mounted thereon, and means connecting the pins to their respective shafts to permit a pin to swing in one direction independently of the rotation of its shaft, together with means to rotate positively all of the said shafts.

2. In game apparatus of the nature set forth: 70 a plurality of parallel, horizontally disposed shafts rotatably supported between the sides of a box-like structure, pins swingably mounted thereon above their respective centers of gravity, and pawl and ratchet means interposed between the pins and their respective shafts, together 75

with means to rotate positively all of the said shafts.

3. In game apparatus of the nature set forth: a plurality of parallel, horizontally disposed shafts rotatably supported between the sides of a box-like structure, pins having respective sleeves passing therethrough for swingably mounting a pin on a shaft, an internal ratchet element movable with a sleeve and its pin, and a spring-urged pawl element carried by a shaft to engage a corresponding ratchet element of a pin, together with means to rotate the said shafts.

4. In game apparatus of the nature set forth: a plurality of parallel, horizontally disposed shafts rotatably supported between the sides of a box-like structure, pins swingably mounted thereon, means connecting the pins to their respective shafts to permit a pin to swing in one direction independently of the rotation of its shaft, and means to rotate all of the respective shafts in a direction opposite that of the swing of the pins.

5. In game apparatus of the nature set forth: a plurality of parallel, horizontally disposed shafts rotatably supported between the sides of a box-like structure, pins swingably mounted thereon, means connecting the pins to their respective shafts to permit a pin to swing in one direction independently of the rotation of its shaft, and means to rotate simultaneously all of the respective shafts in a direction opposite that of the swing of the pins.

6. In game apparatus of the nature set forth: a plurality of parallel, horizontally disposed shafts rotatably supported between the sides of a box-like structure, pins swingably mounted thereon, pawl and ratchet means interposed between the pins and their respective shafts, and an electric motor for rotating the respective shafts in a direction opposite that of the swing of the pins, together with intermediate gearing and a control circuit for the motor.

7. In game apparatus of the nature set forth: a plurality of parallel, horizontally disposed shafts rotatably supported between the sides of a box-like structure, means for mounting thereon pins swingable in one direction independently of the rotation of the shaft, clutching means mounted upon certain of the shafts for communicating the swing of one of a pair of pins to its associated pin, the clutch means operating to permit said associated pin to swing independently of the said one pin when struck by a played ball.

8. In game apparatus of the nature set forth: four parallel, horizontally disposed shafts rotatably supported one behind the other between the sides of a box-like structure, a single pin mounted on the foremost shaft, two pins mounted on the second of the shafts, three on the third of the shafts, and four on the rearmost shaft, said pins being swingable on their respective shafts in one direction independently of the rotation of the shafts, clutching means mounted upon the third shaft and clutching means mounted upon the rearmost shaft for communicating respectively the swing of the intermediate pin on the third shaft to either of its adjacent end pins and the swing of either of the two intermediate pins of the rearmost shaft to its respective adjacent end pin.

9. In game apparatus of the nature set forth: a plurality of parallel, horizontally disposed shafts rotatably supported between the sides of a box-like structure, means for mounting thereon pins swingable in one direction independently of the rotation of the shafts and including a sleeve carried by a pin, certain of said sleeves having juxtaposed clutch teeth for communicating the swing of one of a pair of pins to its associated pin, and operating to permit said associated pin to swing independently of the said one pin when struck by a played ball.

MYRON C. MORRILL.
